CAN OPENER

Hans von Wolfersdorf, Wheaton, Ill.; Johanna von Wolfersdorf, administratrix of said Hans von Wolfersdorf, deceased

Application October 9, 1933, Serial No. 692,736

2 Claims. (Cl. 30—3)

This invention relates to can openers of the manually operable type, and has reference more particularly to a known type of such can openers structurally characterized by a frame plate or 5 bar formed with an inwardly overhanging cutter blade for piercing and cutting out the top wall of the can, and a traction wheel and operating handle therefor journaled in the frame plate and serving to effect a travel of the frame plate and 10 cutter blade around the top edge of the can through biting engagement with the underside of the usual annular bead or rim on the end of the can.

One object of this invention has been to provide a can opener of this type of exceedingly simple construction and few parts, thereby conducting to low cost. Another object has been to provide an improved can opener that may very easily be applied to and removed from the can, 15 and that will effect a smooth and easy cutting operation. A still further object has been to provide a can opener of such construction that, as the top wall of the can is pierced by the cutting blade and the latter shifted to cutting position, 20 the traction wheel will be automatically brought into a position favorable for biting engagement with the lower edge of the bead or rim so as to insure good traction on the latter.

Still other objects and attendant advantages 30 of the device will be apparent to those familiar with tools of this character by the following detailed description, taken in connection with the accompanying drawing in which I have illustrated one practical embodiment of the principle 35 of the invention, and wherein:

Fig. 1 is an inner side elevation of the can 40 opener.

Fig. 2 is an outer side elevation of the same turned end for end.

Fig. 3 is a top plan view of Fig. 1.

Fig. 4 is a view illustrating the first operation of piercing the top wall of the can.

Fig. 5 is a view similar to Fig. 4 but showing the handle swung down to bring the blade into cutting position.

Fig. 6 is an enlarged cross section on the offset line 6—6 of Fig. 5.

Referring to the drawing, 10 designates a handle member preferably of wood and of a size and shape to be held securely in one hand of the operator. Rigidly mounted on the inner end of the handle 10 and extending lengthwise of the latter is a flat frame plate 11 preferably formed with a longitudinal slot 12 in its outer portion. Integral with and continuous with the top edge

of the frame plate 11 is the shank 13 of a cutter blade 14. This blade extends generally lengthwise of the handle and is formed with a lower beveled cutting edge 15 (Fig. 6), and, as best shown in Fig. 3, is preferably outwardly inclined 5 for a purpose later disclosed. The blade is formed with a comparatively sharp piercing end or tip 16.

Rotatably mounted on the inner side of the frame plate 11 is a toothed traction wheel 17 fast on the inner end of the stem or shank 18 of an 10 operating handle 19, the stem or shank 18 being 15 slideable in the slot 12. Integral with the upper edge of the frame plate 11 and directly in rear of the blade 14 is a laterally extending lug 20 that, in the lowered position of the handle shown in Fig. 5 rides on the top edge of the top bead of 20 the can, and on the lower edge of the frame plate 11 is an inwardly extending lug 21 that, as shown in Fig. 6, bears against the vertical wall of the can during the cutting operation to prevent friction between the traction wheel and the can wall. The blade shank 13, as best shown in Fig. 3, is 25 continuous with the lug 20; and, in order to render the blade resiliently yieldable to a small extent, its shank 13 is separated from the frame plate 11 by a longitudinal kerf 22. This characteristic of the blade is not indispensable to a satisfactory functioning of the tool, but has two advantages. In the first place, as the tool is entered on the can and moved to cutting position, its horizontal 30 springiness tends to draw the frame plate carrying the traction wheel snugly against the outer wall of the can; and in the second place, when the traction wheel is turned to engage with the lower edge of the can bead, as shown in Fig. 6, its vertical 35 springiness causes the traction wheel to take a good grip on the bead.

In using the tool for cutting out a can top, it is first applied in a substantially vertical position, as shown in Fig. 4, and downward pressure on the handle causes the blade to puncture the top, the traction wheel and its operating handle at the same time dropping to the lower end of the slot 12 so that the traction wheel lies below the bead. The handle is then swung 45 down to the position shown in Fig. 5, rocking on the shank of the blade as a fulcrum. This slightly raises the traction wheel into engagement with the under side of the bead, and at the same time starts the cutting operation by 50 causing the cutting edge 15 of the blade to sever a portion of the can top. The user, grasping the handle 10 with one hand, turns the operating handle 19 clockwise (viewing Fig. 2) with the other whereupon the traction wheel first 55

travels to the inner end of the slot 12, and, as soon as it abuts the inner end of said slot, the grip of the wheel on the bead causes the can to rotate, thus effecting a complete severance of the can top close to the inner wall of the can body. When the top has been completely severed, a slight turning movement of the handle 19 in the opposite direction causes the traction wheel to ride to the outer end of the slot 12 and thus frees the tool completely from the can body.

While I have shown and described one specific form of the invention which, in practice, has been found to satisfactorily effectuate the stated purposes and objects thereof, it is manifest that the structural details may be considerably varied without involving any departure from the principle of the invention, and hence I do not limit the latter to the device as shown, except to the extent indicated in specific claims.

I claim:

1. A can opener, comprising a handle, a flat frame plate rigidly mounted on one end of said handle and extending lengthwise of the latter and having a straight longitudinal slot, a fixed cutter blade mounted on and inwardly offset from said frame plate, said blade lying opposite said slot and extending generally lengthwise of said handle and formed with a pointed end for piercing the can under a down thrust on said handle, a traction wheel operating handle having a shank rotatably and slidably mounted in said slot, a traction wheel fast on the inner end of said shank, said slot, through engagement with

said shank, operating to raise said traction wheel into biting engagement with a bead on the can when said first-named handle is swung downwardly, and an upper lug on said frame plate adapted to rest on the top edge of the can when said first-named handle is in substantially horizontal position.

2. A can opener, comprising a handle, a flat frame plate rigidly mounted on one end of said handle and extending lengthwise of the latter and having a straight longitudinal slot, a fixed cutter blade integral with the top edge of said plate and inwardly offset from the latter opposite said slot, said blade extending generally lengthwise of said handle and being resiliently yieldable both vertically and horizontally and formed with an outwardly inclined pointed end portion for piercing the can under a down thrust on said handle, a traction wheel operating handle having a shank rotatably and slidably mounted in said slot, a traction wheel fast on the inner end of said shank and lying against the inner side of said frame plate, said slot, through engagement with said shank, operating to raise said traction wheel into biting engagement with a bead on the can when said first-named handle is swung downwardly, an upper lug on said frame plate adapted to rest on the top edge of the can when said first-named handle is in substantially horizontal position, and a lug on the lower edge of the frame plate adapted to bear on the side wall of the can.

HANS VON WOLFORDS DORF.
